UNITED STATES PATENT OFFICE

161,703

LINK TYPE RUBBER MAT

Dudley W. Moor, Jr., Toledo, Ohio, assignor to
 American Mat Corporation, Toledo, Ohio, a corporation of Delaware

Application November 22, 1950, Serial No. 13,094

Term of patent 14 years

(Cl. D9—6)

To all whom it may concern:

Be it known that I, Dudley W. Moor, Jr., a citizen of the United States residing at Toledo, in the county of Lucas, State of Ohio, have invented a new, original, and ornamental Design for a Link Type Rubber Mat, of which the following is a specification, reference being had to the accompanying drawing, forming a part hereof.

Fig. 1 is a top plan view of a link type rubber mat, showing my new design.

Fig. 2 is a fragmentary top plan view, to an enlarged scale, of the lower right-hand corner of the mat shown in Fig. 1.

Fig. 3 is a perspective view, to an enlarged scale, of one of the links in the mat shown in Fig. 1.

The bottom of the mat has the same design as the top.

I claim:

The ornamental design for a link type rubber mat, as shown and described.

DUDLEY W. MOOR, JR.
